UNITED STATES PATENT OFFICE.

MAURICE MATHY, OF FLÉMALLE-GRANDE, BELGIUM.

APPARATUS FOR HEATING BY COMBUSTION WITHOUT FLAME.

1,388,355.

Specification of Letters Patent. Patented Aug. 23, 1921.

Application filed April 4, 1919. Serial No. 287,657.

To all whom it may concern:

Be it known that I, MAURICE MATHY, manufacturer, a subject of the Kingdom of Belgium, and resident of Flémalle-Grande, 5 in the Kingdom of Belgium, have invented certain new and useful Improvements in Apparatus for Heating by Combustion Without Flame; and I do hereby declare the following to be a full, clear, and exact description of the invention, such as will enable others skilled in the art to which it 10 pertains to make and use the same, reference being had to the accompanying drawings, and to letters or figures of reference 15 marked therein, which form a part of this specification.

The present invention relates to apparatus for heating by combustion without flame, in which a gaseous mixture burns in the heart 20 of a mass of fragments of porous refractory material. It relates more particularly to the regulation in such apparatus of the temperature obtained in the various parts to be heated. This regulation of the temperature 25 according to circumstances may in particular be of great importance in various metallurgical or chemical operations. It is applicable for instance in the case of enameling an article one of the faces of which has to 30 be enameled with an enamel having a melting point different from that of the enamel covering the other faces.

The desired result may be obtained by applying the observed fact that is the case of 35 the flameless combustion of a gaseous mixture in the heart of a mass of fragments of porous refractory material the temperature obtained is the higher according as the fragments of refractory porous material amongst 40 which and in which the gaseous mixture circulates are smaller in size. This is explained by the fact that in the latter case the gases undergo a much more intimate mixing than in the case where the above- 45 mentioned fragments are of greater size.

It is to be observed that by taking this fact as a basis it is also possible to obtain a uniform temperature throughout the path of the gases in the mass of the said fragments by making the size of the fragments decrease from the place where the gases enter to the place where they leave.

Moreover the invention also provides for a flameless-combustion heating apparatus 55 the wall of which is divided into a number of sections forming boxes containing refrac-

tory material in fragments of a definite size. The gaseous mixture may be either introduced into each of these boxes separately or may circulate from one to the other. 60

The drawings accompanying the present specification show, by way of example, certain constructional forms of the invention. In these drawings:

Figure 1 is a vertical section through the 65 axis of an apparatus serving to heat a crucible.

Fig. 2 is a vertical section through the axis of an apparatus serving to heat a crucible in another application of the invention. 70

Fig. 3 is a horizontal section through a muffle furnace.

Fig. 4 is a horizontal section through a muffle furnace in another application of the invention. 75

Fig. 5 is a horizontal section on line 5—5 in Fig. 6 of a furnace consisting of separate boxes assembled together.

Fig. 6 is a vertical section on line 6—6 in Fig. 5 of the same furnace, and 80

Fig. 7 is a sectional elevation through the axis of a crucible placed in a crucible furnace for glassware.

Fig. 1 relates to the case in which predetermined temperatures have to be obtained 85 in particular parts of the crucible 1. The gaseous mixture passes through one of the apertures 3 or 4 in the furnace 2 and burns while passing through the mass of fragments of porous refractory material interposed between the said crucible 1 and the walls of the furnace 2. In order to heat the regions H, I, J and K of the crucible more intensely the fragments of refractory material located at 5, 6, 7 and 8 are made 90 smaller than those located in the neighborhood of the regions of the crucible not requiring to be heated to such a high temperature. 95

Fig. 2 relates to the case in which the temperature has to be uniform throughout the height of the crucible 9. With this end in view, in order to remedy the progressive impoverishment of the gases as they penetrate into the mass of fragments of porous refractory material and begin to burn, the fragments of the abovementioned material decrease in size from the entrance 10 of the gases right to their outlet 11. 100

Fig. 3 relates to a muffle furnace in which 110 the side 13 of the article 12 has to be heated to a higher temperature than the sides 14 and

15. With this end in view the fragments of porous refractory material between the walls 16 of the said furnace and the wall 17 of the muffle are smaller at 18 than at 19 and 20.
- 5 In the case of Fig. 4, which also relates to a muffle furnace, the fragments of porous refractory material are arranged in such a way that the highest temperature is produced against the walls of the muffle 23. Moreover 10 the cover of this furnace consists of a box inside which flameless combustion also takes place.
- In this way the heating part completely surrounds the body 22 to be heated. In order 15 to insure the production of the highest temperature toward the interior of the furnace the smallest fragments of porous refractory material are arranged against the walls of the muffle 23 and the largest against the walls 20 24 of the furnace.

The outer wall 21 of the box, constituting the cover of the said furnace, is of the same material as the wall of the furnace and of substantially equal thickness. The inner wall 25 25 of the said box is of the same material as the wall of the muffle and of substantially equal thickness. The sides 26 and 27, which are inclined at 45°, as are the walls 28 and 29, which serve to retain the fragments of 30 porous refractory material, consist of porous plates or of plates pierced with holes in such a way as to allow the gaseous mixture to flow through the spaces E, F and G. The lower and upper faces of the said box are 35 made either of porous plates or plates pierced with holes or else of material similar to that which constitutes the walls of the furnace.

It is to be observed that the walls 17 and 23 of the muffles shown in Figs. 3 and 4 respectively may also be pierced with holes of larger or smaller size so as to insure more direct heating (by radiation for example) of the body to be heated.

It is to be observed that if the muffle is of 45 porous material the combination will also be able to take place in the wall of the said muffle.

In the case of Figs. 5 and 6, the furnace is formed by assembling boxes similar to the 50 one that serves as a cover for the muffle furnace in Fig. 4. The furnace consists of six boxes 30, 31, 32, 33, 34 and 35 forming the six faces of a rectangular parallelepiped. The walls of these boxes designated by the 55 letter L each consist of a refractory plate or of a plate pierced with holes in such a way that the gases can circulate all around the

body 36 to be heated. The said gases will enter through one of the two openings 37 and 38 and will leave by the other.

It goes without saying that a furnace arranged in the manner specified above may be constructed around the article to be heated without displacing the latter.

In the case of the application illustrated in Fig. 7 the front wall of a furnace 41 for a crucible 40 for glassware consists of a box 39 similar to the one that serves as a cover to the furnace and muffle shown in Fig. 4.

This arrangement is particularly advantageous for the purpose of facilitating the removal of the crucible 40.

What I claim is:

1. Heating apparatus comprising a mass 75 of fragments of different sizes of porous, refractory material, in the heart of which flameless combustion of a gaseous mixture takes place; said mass embodying different definite zones in which the fragments of small size are arranged, to obtain particularly high temperatures in such zones.

2. Heating apparatus for burning a gaseous mixture, comprising a mass of fragments of different sizes of porous, refractory material; the fragments progressively decreasing in size from the point where the gases enter the apparatus to the point where they leave it, to obtain an uniform temperature throughout the path of the gases in said mass.

3. A furnace having one or more of its heating walls in the form of boxes containing a mass of fragmentary porous, refractory material in the heart of which flameless combustion of a gaseous mixture takes place.

4. A furnace having heating walls formed by mutually-contacting boxes containing masses of fragmentary porous, refractory material in the heart of which flameless combustion of a gaseous mixture takes place, the contacting walls of the boxes being constructed to permit the gases to pass from one box to another.

5. In a furnace heated by the flameless combustion of a gaseous mixture in the heart of a mass of fragments of porous refractory material, a cover consisting of a box inside which flameless combustion takes place.

In testimony whereof I affix my signature in presence of two witnesses.

MAURICE MATHY.

Witnesses:
